UNITED STATES PATENT OFFICE

ARTHUR RICHTER, OF BERBISDORF, GERMANY

HIGH-SPEED FLAT HOSIERY FRAME

Application filed July 20, 1927, Serial No. 207,216, and in Germany May 2, 1927.

This invention has for its object to make the flat hosiery-frame for instance the cotton-frame, run much more rapidly, a good fabric being nevertheless produced. It has 5 already been proposed to increase the working speed of the hosiery-frame, but these attempts were limited as the formation of the loops requires a certain time up to the knocking over. It has been proposed to shorten the 10 needle, but herefrom resulted difficulties at the pressing. According to the present invention the same time as usual is allowed for the formation of the loop and the needle is of the usual length. The higher working 15 speed of the machine is obtained by making the needle execute a shorter movement, for instance half the travel as hitherto, however, in order that a good loop be formed up to the knocking over, the machine head with the 20 knock-over comb move towards the needle path, i. e. ascend while the needle is descending.

Suppose the needle descends actually on the cotton-frame 25 mm., in this case it will 25 ascend also 25 mm. so that the entire travel amounts to 50 mm. According to the present invention the travel of the needles will be only 25 mm., as the mechanism for forming the loops comes to meet the needle half way. 30 The machine can consequently run at double the speed of the ordinary machine, and all the working operations, as sinking of the loops, dividing, pressing and knocking over, are carried out in accurately the same time as with 35 the normal working method, so that the fabric is of the same good quality as when the machine is working at slower speed.

An embodiment of the invention is illustrated by way of example, in the accompanying drawing in which:—

Fig. 1 shows a cotton-frame-head in sectional side elevation, the needle being in the highest position,

Fig. 2 is a similar view, showing the needle lowered, the machine head with press and knock over comb having ascended accordingly.

The frame-head 2, in which the sinkers 3 move and on which also the presser-bar 4 and 50 the knock over comb 5 are mounted, is, for

instance in the cotton-frame, arranged so that it can move up and down, for instance execute half the travel which the needle executes in the normal cotton frame. This movement is controlled by a cam 6 mounted 55 on the main shaft of the frame, and through the intermediary of levers 7 and 8 controlled by a spring 9.

The movement is preferably intermittent or stepwise so that the frame-head ascends 60 first half its travel (step 10 on the eccentric 6), i. e. up to the pressing, whereupon the second step of the movement is carried out up to the knocking over (step 11 on the eccentric 6). A correct working of the frame is thus 65 ensured. The sinkers are guided in a guide box 12 shiftable in the axial direction of the needles.

I claim:—

1. A flat hosiery frame, comprising a 70 needle bed with needles, sinkers co-operating with the needles to form loops, and means for moving said sinkers not only transversely to the axial direction of said needles but also together with said needle bed in the axial direction of the needles.

2. A flat hosiery frame as specified in claim 1, comprising in combination with the sinkers, a cam shaft, a cam mounted on said cam shaft for shifting said sinkers in axial direction of the needles.

3. A flat hosiery frame as specified in claim 1, comprising in combination with the sinkers, a cam shaft, a cam mounted on said cam shaft for shifting said sinkers in several steps, 85 first up to the beard pressing position and then up to the knocking over position.

In testimony whereof I affix my signature.

ARTHUR RICHTER.
